RAZOR BLADE SHARPENER

Filed May 2, 1947

Inventor,

James T. King,

Albert E. Dutcher,

Attorney.

UNITED STATES PATENT OFFICE

2,461,161

RAZOR BLADE SHARPENER

James T. King, Burbank, Calif.

Application May 2, 1947, Serial No. 745,401

4 Claims. (Cl. 51—80)

1

My invention relates to devices for use in sharpening razor blades of the double-edge wafer or "Gillette" type.

The objects of the present invention are:

1. To provide a simple inexpensive device so designed that its parts can be made of accurate plastic die cast parts.

2. To provide a sharpener of such construction that the correct angle of the two edged blades is sharpened for either the hollow ground or wedge shaped blade edges.

3. To provide a sharpener having two rollers, one of which is turned on a fixed axis by a handle while the other is in full floating contact with the driving roller and is driven thereby, the floating roller being held in contact by means of a spring wire hooked to the base of the case, and engaging the ends of the floating roller to constitute an axle for the roller.

4. To provide a blade holder or loading device which is fully spring-loaded so that when the blade is pressed down for sharpening on the leather spirals, the correct angle is automatically brought about to properly hone the blade edges.

5. In general to provide an efficient razor blade sharpener that can be manufactured at low expense as compared to those sharpeners now on the market.

To the attainment of the aforesaid objects and ends, invention resides in the novel details of construction, combinations and arrangements of parts which will hereinafter be first described and then be particularly pointed out in the appended claims, reference being had to the accompanying drawing in which:

Fig. 1 is a top plan view of my invention with a blade in place.

Fig. 2 is a longitudinal section on the line 2—2 of Fig. 1.

Fig. 3 is a cross section on the line 3—3 of Fig. 2.

Fig. 4 is a top plan view of the case, the roller holding spring and the blade holder loading springs in place.

Fig. 5 is a detail section on the line 5—5 of Fig. 4.

Fig. 6 is a section looking from right to left in Fig. 5.

Fig. 7 is a side elevation of the device, some internal parts being shown in dotted lines.

Fig. 8 is a detail elevation of the blade holder.

In the drawing in which like numerals of reference indicate like parts in all the figures, 1 represents the case whose wall is reinforced or thickened, as at 2, the portions 2 lying equidistant from the mid-transverse plane of the case. One

2

of the reinforcements 2 is bored through as at 3 and 4 to receive the bearing parts of a crank shaft 6. The shaft 6 is of two diameters, the larger 6^a being threaded and the lesser 6^b being non-threaded (see Fig. 1). The shaft 6 is provided with a crank arm 6^c and hand engageable roller 6^d as shown.

Each sharpening roller 7 is of the same diameter and has a spiral groove 7^a in which is tightly fitted and cemented, a leather strap 8.

The straps 8 and the intervening spaces are, preferably, of the same width as shown. Each roller 7 has a hub 7^b bored as at 7^c, one roller being counterbored and threaded as at 7^d to receive the crank shaft 6. Each roller 7 also has a rim 7^e in which the groove 7^a is molded or cut.

The side walls of the case are provided with vertical grooves 9 and inclined projections 10 to receive the spring wire roller floater, which 20 floater includes a transverse portion 12 that fits under a hook 14 formed on the bottom of the case at the middle. The floater also has arms 13 which lie on the bottom of the case 1 and extend from the mid-transverse plane of the case to a point directly under the axis of the roller. The arms 13 merge with upwardly extended arm portions 14 having short ends 15 bent one toward the other to constitute trunnions 16 which fit into the ends of the bores of the floating roller and 30 continuously tend to maintain it in contact with the driving roller that is located on the crank shaft 6. The projections 10 terminate short of the bottom of the case to provide spaces to receive the arms 13. Further, each projection 10 has a rounded corner 10^a and an inclined side 10^b designed to permit the vertical arm ends 14 to have movement in grooves 9 toward the driving roller to maintain pressure contact between the two rollers 7 so that the one will drive the other.

40 The case, midway its ends, has two side pockets 17 to contain coil springs 18, the pockets being recessed at the top a predetermined depth as at 19 to receive the cross-bar 20 of the blade holder and guide.

45 The bar 20 has lugs 21 to fit into the coil springs 18 and it has a tapered rib 22 to project down between the rollers 7 (see Figs. 2 and 3). It also has a top rib 23 and lugs 24 to fit the slot and holes of a wafer blade B to be sharpened. The 50 blade B may be manually held down on the bar 20 but I prefer to provide a leaf spring clip 25 for the purpose. This clip is secured at one end to the bar, as at 26, and is slotted as at 27 to fit over the rib 23 and lugs 24 and press the blade B down 55 on the bar.

Operation

After placing the blade **B** on the holder, the user of the appliance holding the case in one hand, places the bar **28** in the recesses **19** and with his thumb presses the holder down until the blade's edges **b** engage the leather straps **8**. He then turns crank **6** to turn the rollers to strop the blade edges. The depth of the recesses **19** determines the maximum bend that can be given the blade to present a predetermined fixed angle of contact with the rollers. To strop the other face of the blade edges the blade is removed, turned over and replaced on the holder and the aforesaid process is repeated.

From the foregoing description taken in connection with the accompanying drawing it is thought the construction, operation and advantages of the invention will be clear to those skilled in the art.

What I claim is:

1. In a wafer blade sharpening machine, a case; a crank shaft journalled in suitable bearings in said case; a sharpening roller on said crank shaft; a floating sharpening roller in said case; spring means holding said floating roller in contact with said first mentioned roller, said means comprising a hook on the bottom of the case, a roller floater having a transverse portion located under the hook and having arms lying against the bottom of the case, said arms having upward extensions terminating in ends bent over toward one another and forming trunnions for said floating roller, and projections on walls of the case for holding said floater against pivoting on said hook; and means movably engaging said case for presenting a blade to said rollers to be sharpened thereby.

2. In a razor blade sharpening machine wherein is provided an open top case, two stropping rollers located in said case, a fixedly located crank shaft carrying one of said rollers and mounted in bearings in said case, the improvement which comprises a resiliently mounted axial support for the other of said rollers, which support has provision for exerting a contacting force of one roller against the other whereby the roller on the crank shaft will drive the other roller, said resiliently mounted support comprising a spring-wire member having a cross-bar portion, two parallel legs extending along the bottom of the case, said legs having upward extensions with ends bent over toward one another as trunnions for said other of said rollers, and means to anchor said cross-bar portion and said two parallel legs to said case.

3. In a razor blade sharpening machine wherein is provided an open top case, two stropping rollers located in said case, a fixedly located crank shaft carrying one of said rollers and mounted in bearings in said case, the improve-

ment which comprises a resiliently mounted axial support for the other of said rollers, which support has provision for exerting a contacting force of one roller against the other whereby the roller on the crank shaft will drive the other roller, said resiliently mounted support comprising a spring-wire member having a cross-bar portion, two parallel legs extending along the bottom of the case, said legs having upward extensions with ends bent over toward one another as trunnions for said other of said rollers, and means to anchor said cross-bar portion and said two parallel legs to said case, said anchoring means comprising a hook on the bottom of the case for holding said cross-bar portion, and side wall projections of the case for holding down said parallel legs on the bottom of the case.

4. In a razor blade sharpening machine wherein is provided an open top case, two stropping rollers located in said case, a fixedly located crank shaft carrying one of said rollers and mounted in bearings in said case, the improvement which comprises a resiliently mounted axial support for the other of said rollers, which support has provision for exerting a contacting force of one roller against the other whereby the roller on the crank shaft will drive the other roller, said resiliently mounted support comprising a spring-wire member having a transverse bar portion, a pair of horizontal side legs, having upwardly extended leg portions terminating in trunnion members extending toward one another and parallel to said bar portion, a member on the bottom of the case to engage and hold said transverse bar portion, members on the sides of the case to engage said horizontal side legs and hold them down, said case having vertical grooves to receive said upwardly extended leg portions and permit said trunnion members to move said other of said rollers toward the roller that is carried by the crank shaft.
